UNITED STATES PATENT OFFICE.

LOUIS ENSINGER, OF LITTLE ELM, TEXAS.

BALING-PRESS.

SPECIFICATION forming part of Letters Patent No. 252,200, dated January 10, 1882.

Application filed October 26, 1881. (No model.)

To all whom it may concern:

Be it known that I, LOUIS ENSINGER, of Little Elm, in the county of Denton and State of Texas, have invented a new and useful Improvement in Baling-Presse, of which the following is a full, clear, and exact description.

Reference is to be had to the accompanying drawings, forming part of this specification, in which similar letters of reference indicate corresponding parts in all the figures.

Figure 1, Sheet 1, is a sectional side elevation of my improvement. Fig. 2, Sheet 1, is a sectional plan view of the same, taken through the broken line $\alpha\alpha$, Fig. 1. Fig. 3, Sheet 1, is a plan view of the same, parts being broken away. Fig. 4, Sheet 2, is an elevation, partly in section, of the tail end of the press. Fig. 5, Sheet 2, is an elevation of the driving-gearing.

The especial object of this invention is to economize time, labor, and expense in baling cotton and other substances.

A represents the end frame of the head of the press, which is formed of two main sills and three cross-pieces securely bolted together. The end frame B at the tail of the press is formed of two main sills and two cross-pieces securely bolted together. The end frames, A B, are connected at their corners by four iron rods, C, each of which has two nuts at each end, one upon each side of an end frame. The intermediate frame, D, is formed of sills and cross-pieces bolted to each other, and to which are attached the planks E, that form the baling-box. To the cross-pieces of the head-frame A are attached narrow planks F, that form the head-block, the said planks being placed at such a distance apart as to form spaces between them to receive the bale-bands. A similar set of planks, G, is secured to the forward side of the follower H, which is formed of two blocks securely bolted to each other. The follower H is made a little smaller than the interior of the baling-box E to allow the bagging to be put around it. The follower H is supported while moving forward and back by small rollers I, pivoted to bearings attached to the rear side of the said follower, the said wheels rolling along metallic straps or plates J, attached to the bottom of the said baling-box E. The side edges of the follower H are kept from contact with the sides of the baling-box by roll-

ers K, pivoted to bearings attached to the side parts of the rear side of the said follower.

To the rear side of the follower H is attached the forward end of the bar L, which has gear-teeth upon its sides and passes between guide-rollers M, pivoted to bearings attached to the tail-frame B in such positions that the faces of the said rollers M will bear against the upper and lower sides of the said bar, and thus cause it to move forward and back in a straight line, so that the follower H will always be in a vertical position.

N are two gear-wheels placed upon the opposite sides of the rack-bar L, with their teeth meshing into the teeth of the said rack-bar L. The gear-wheels N are attached to two vertical shafts, O, which revolve in bearings attached to the tail-frame B. To the upper ends of the shafts O are attached worm-wheels P, the teeth of which mesh into the worms or screws Q, formed upon or attached to the shaft R. One of the worms Q is made with a right and the other with a left screw-thread, so that the worm-wheels P, and with them the gear-wheels N, will turn in opposite directions, and will thus operate together to move the rack-bar L and follower H forward and back. The shaft R revolves in bearings attached to the tail frame B, blocks being interposed between the said bearings and frame to raise the shaft R to a proper height.

One end of the shaft R projects, and to it are keyed or otherwise securely attached a large internally-toothed gear-wheel, S, and a small gear-wheel, T, as shown in Fig. 4. Between the internal teeth of the gear-wheel S and the external teeth of the gear-wheel T is placed a gear-wheel, U, of such a size that it can be placed between the two gear-wheels S and T without being in gear with either. With this construction, when the gear-wheel U is in gear with the gear-wheel T the follower H will be moved with greater speed and less power, and when the said gear-wheel U is in gear with the gear wheel S the said follower H will be moved with less speed and greater power.

The gear-wheel U is keyed or otherwise secured to the driving-shaft V, the outer end of which revolves in a bearing attached to a post or upright frame, W. The inner journal of the shaft V revolves in a bearing attached to the

middle part of a bar, X, which is hinged at one end to and between two posts of the upright frame Y. The other end of the bar X moves up and down between two posts of the said upright frame Y, so that the gear-wheel U can be thrown into gear with either of the gear-wheels S T and out of gear with both of the said gear-wheels by adjusting the said bar X.

To the upper side of the free end of the bar 10 X, or to a support attached to the said bar, is hinged the lower end of a connecting-bar, Z, the upper end of which is hinged to the end of an arm, a, rigidly attached to the rod b. The rod b extends across the machine and works 15 in bearings attached to the frame Y and to a bar, c, attached to the tail-frame of the press or other suitable support. To the end of the rod b is attached an upwardly-projecting lever, d, which moves along an arched or semicircular catch-plate, e, attached to the support c. The catch-plate e has three notches formed in it to receive a spring lever-pawl, f, connected with the lever d. With this construction, by 20 operating the lever d the wheel U can be thrown into gear with either of the wheels S T and out of gear with both of said wheels, and will be held securely in either of the said positions.

To the shaft V are attached three pulleys, g h i, the central one, h, of which is fast, and 30 the other two are loose. One of the loose pulleys, as g, is designed to receive a straight belt, j, for driving the follower H forward, and the other loose pulley, i, is designed to receive a crossed belt, k, for moving the said follower back. Each of the belts j k passes between 35 two fingers, l, attached to a rod, m, to which they are secured by set-screws or other suitable means that will allow them to be adjusted. The two pairs of fingers l are at such a distance apart that when the belt-shifter is in the 40 position shown in Figs. 2 and 4 both belts are upon the loose pulleys and the follower is stationary. With this arrangement, if the belt-shifter be moved to the right in Fig. 4 the 45 straight belt j will be moved to the fast pulley h and the follower H will be forced forward; or if the belt-shifter be moved to the left, the crossed belt k will be moved to the fast pulley h and the follower H will be drawn back.

The rod m slides in bearings attached to the frame of the press or other suitable supports, and its end is pivoted to the end of an arm, n, attached to the upright rod o, which 55 works in bearings attached to the frame of the press or other suitable supports. To the lower part of the upright rod o is attached an arm, p, projecting at right angles, or nearly at right angles, with the arm n, and having a rod, q, pivoted to its end. The rod q slides in and passes through a bearing in the tail-frame B of the press, and its inner end projects so as to be struck by the follower H as it completes its rearward movement to move both belts 60 to the loose pulleys and stop the said rearward movement of the said follower. To the

upper part of the upright rod o is attached an arm, r, parallel with the arm p and at right angles with the arm n. To the outer end of the arm r is pivoted the end of a rod, s, which 70 extends forward to the head of the press, so that it can be conveniently reached and operated by the pressman to shift the belts as required, the belts being always shifted by hand, except in the single instance that the said 75 belts will be shifted automatically when the follower completes its rearward movement.

The forward part of the baling-box E is formed of four doors, the top and bottom doors, t, being connected with the intermediate sills 80 by two hinges, as shown in Fig. 3, and the side doors, u, being connected with the intermediate side pieces by single hinges. To straps attached to the forward corners of the top and bottom doors, t, are hinged hooks v, which 85 hook into the eyes w of straps attached to the forward corners of the side doors, u, and thus fasten the four doors firmly together. The top and bottom doors, t, are further secured in place by the bars x, (two to each door,) 90 which are pivoted at their inner ends to the said doors in such positions that their outer ends can be swung out beneath the tie-rods C, as shown in full lines in Fig. 3, and swung in to allow the said doors to be opened, as 95 shown in dotted lines in the said Fig. 3.

In the upper rear part of the press-box E is formed an opening, through which the cotton to be pressed is introduced. To the press-frame at the four corners of the inlet-opening are secured four short posts, y, the upper ends of which are connected in pairs by inclined cross-boards z, to serve as guides in introducing the cotton. To the lower edges of the boards z are hinged the outer edges of two doors, 1, the inner edges of which meet, when the said doors are raised, to cover the inlet-opening, as shown in Figs. 1 and 3. The doors 1 are supported, when raised, by bars 2, pivoted at their upper ends to the ends of the said doors, and the lower ends of which rest upon the boards 3. The doors 1, when opened, hang in vertical positions and serve as guides to the cotton in entering the inlet-opening of the baling-box. The boards 3 cover the spaces between the sides of 105 the baling-box E and the tie-rods C and prevent any cotton from dropping through the said spaces.

When a condenser is used the cotton may 110 be conducted from the condenser to the opening in the baling-box by an inclined apron or chute, as indicated in dotted lines in Fig. 1, so as to avoid the labor of putting the cotton into the press by hand.

In using the press, as often as the rear part 115 of the baling-box becomes filled the cotton can be quickly packed into the forward part of the said baling-box by throwing the gear U into gear with the small gear-wheel T, and when enough cotton for a bale has been packed into 120 the baling-box the gear U can be thrown into gear with the large gear-wheel S and the cot-

ton compressed into a bale. By raising the doors 1 each time the follower begins to move forward the cotton will be stopped by the said doors, and thus kept from entering the baling-box in the rear of the follower. When the follower has completed its rearward movement the doors 1 can be lowered and the accumulated cotton allowed to drop into the baling-box, so that the condenser can be run continuously.

Having thus described my invention, I claim as new and desire to secure by Letters Patent—

1. The combination, with the follower H, of the double rack-bar L, the two pinions N N on shafts O, the worm-wheels P, and the reversely-threaded screws Q Q on the rotary shaft R, whereby the follower is reciprocated, as described.

2. The combination, with the shaft R and gear-wheels S T U, of the shaft V, the hinged bar X, the hinged bar Z, the rod b, having arm a, the lever d, and the ratchet and pawl e f, whereby the gear-wheel U can be thrown into gear with either of the wheels S T, as described.

3. The combination, with the fingers l m, 25 of the rod o, having arms n p, placed at right angles to each other, the rod q, pivoted to the end of arm p and passing through a bearing in frame B, and the follower H, arranged to strike said rod q, as and for the purpose specified.

4. The combination, with the top and bottom doors, t, of the tie-rods C and bars X, the latter pivoted to said doors and adapted to swing out under the tie-rods, as and for the 35 purpose specified.

5. The four short posts y, connected in pairs by inclined cross-boards z, in combination with the two doors 1, hinged to the boards z, the bars 2, pivoted to said doors, and the boards 40 3, arranged as shown and described.

LOUIS ENSINGER.
